ELECTRIC FAN

William M. Young, Harrisburg, Pa.

Application August 27, 1934, Serial No. 741,696

5 Claims. (Cl. 230—254)

My present invention, in its broad aspect, has to do with improvements in electric fans of the type designed to rotate on a fixed base to direct air currents radially through all degrees of a circle, and which is further adjustable to regulate the plane of the air blast angularly with respect to the axis of circular rotation of the fan, and which has means for automatically controlling the speed of rotation of the fan; furthermore my fan assembly may be converted by a simple adjustment into a single direction fan, and rotational movement is produced by air back pressure from the fan, while the braking action is controlled by the centrifugal force generated by the circular movement of the fan assembly whereby the extent of braking action is in direct proportion to the speed of rotation.

There are a number of problems confronting the originator of a practical, universally rotating breeze fan; some of these are 1st to attain the required simplicity for economical production, sale and every-day use; 2nd, to insure at all times continuous electrical in-put to the fan motor despite rotation of the fan assembly, and to properly insulate the circuit; 3rd, to avoid fragility of parts and at the same time attain compactness to the end that the assembly will stand continuous operation and hard usage by persons essentially unfamiliar with the operation and care of machinery, and attain lightness and ready portability; 4th, to provide for pleasing appearance and at the same time protect the parts from damage, dust and the like, so that the fan may be treated as an ordinary and conventional household appliance; 5th, to attain automatic control and operation without complicating its structure and proper functioning simply by cutting in the current, so that a person normally unfamiliar with the intricacies of machinery may operate the fan satisfactorily and safely; and 6th, to attain maximum circulation of air not only in the plane of the circular path of rotation, but in other planes tangential or angular thereto whereby parts of a room or the like may be served by the fan effectively without considering niceties of placement of the fan assembly.

It is believed that my present invention effectively solves all of the problems briefly outlined above, and in addition insures economical operation either as a rotating fan or as a direct stationary air blast fan, but additional advantages will be apparent from the following detailed description of the invention taken in conjunction with the drawing forming a part of this application. However, since unforeseen practical exi-

gencies may indicate changes in form, size, shape and position of parts without departing from the spirit of the invention as herein broadly outlined; it is to be understood that such changes are permissible provided they are within the purview 5 of what is claimed.

In the drawing wherein I have shown a preferred form of my invention;—

Figure 1 is a vertical section therethrough with part of the fan structure shown fragmentarily: 10

Figure 2 is a side view of the fan assembly;

Figure 3 is a plan view looking down toward the rotating fan pedestal and the base;

Figure 4 is a detail of the current in-put;

Figure 5 is a modified form of fan mounting. 15

In the drawing, wherein like characters of reference are used to designate like or similar parts throughout the several views;—

The numeral 1 designates the stationary base of the fan assembly which is preferably circular 20 in plan view, but which may be square or irregularly shaped if desired. The base is flanged down as at 2 to provide a space 3 beneath the top 4 thereof so that the in-put wires 5 and 6 will not come into contact with a table or the like upon 25 which the fan may be placed.

The positive and negative terminals 5 and 6 of the composite cable 7 are attached to electrical fittings 8 and 9 positioned in the top 4 of the base. Each fitting includes a cylindrical insulating 30 member 10 rigidly fixed in the top of the base and a square bushing 11 to which the cable ends connect; a square contact member 12 is carried in each member 10 and is maintained in position by spring 13 engaging ball fitting 14 at one end 35 and the cable terminal at the other. Rising vertically from the center of the top 4 of the base is a standard 15 upon which the rotating unit 16 of my fan is mounted in a manner which will hereinafter appear. 40

Carried by the standard 15 and having anti-frictional support thereon as at 17 is a tubular, cylindrical carriage 18 extending practically the length of the standard and designed to freely revolve thereon. Fixed on the upper end of the 45 carriage is an arm 19 having end-ball-thrust-bearing contact 20 with the end of the standard as shown to properly position and retain the assembly. Also attached to the carriage 18 is an insulating collar 21 in the under surface of 50 which are embedded circular contact rings 22 and 23 having wiping, continuous contact with contact members 12 of fittings 8 and 9 respectively, and which in turn are connected with electrical fittings 24 and 25 for positive and negative con- 55

nections 26 and 27 to the fan motor 28. Fittings 24 and 25 are each formed with a brass receptacle 29 a plunger 30 and an insulating piece 31 through which the cable end is carried to engagement with the plunger part 30. Both fittings are alike and current is continuously passed in an economical manner therethrough to the motor 28 irrespective of rotation of the fan assembly. The motor 28 has spaced depending legs 28a fixed to 10 pivoted bracket 32 on the arm 19 carried by the carriage 18, and said pivoted bracket has a depending leg 33 coupled with a transversely positioned pin or link 34 which extends through an opening in the carriage and has its end engaged 15 with the standard 15. The pin is provided with screw threads 35 and an adjusting nut 36 there being a spring 37 about the pin 34 which engages at one end the wall of the carriage 18 and at the other against the nut 36.

20 The fan 38, fan guard 39 and motor 28 are supported on the pivoted bracket 32 so that the pin 34 is normally out of contact with the standard 15 against the pressure of the spring 37; when the current is applied and the fan is in operation the 25 back pressure, acting through the arm 19 causes the carriage and all the other rotating parts to revolve about the standard 15, in which case the centrifugal action or force acting upon the motor and fan assembly acts through pivoted bracket 30 to press the end of the pin 34 against the standard 15 thereby braking the rotational movement of the assembly so that proper operation is obtained.

If it is desired to use the fan as a fixed direction fan, the thumb nut 40 is tightened up—same 35 extending through the carriage 18 to engagement with the standard 15 to lock the rotational parts against movement.

In order that the fan (and motor assembly) 40 may be adjusted to generate a draft in planes other than defined by the rotational movement, I have provided a pivotal attachment between the depending legs 28a of the motor and the bracket 32, same including a pin 41, a bushing 42 about 45 the pin 41 and a wing nut 43 so that the motor and fan assembly can be manually adjusted by simply loosening up the wing nut. In the form shown in Figure 5 the motor and fan assembly are simply bolted as at 44 to the arm 19 and the 50 angular position of the fan adjusted by nut 43. No centrifugal brake is used with this form, and the various speeds of circular movement are controlled by turning the motor and fan assembly at various angles in relation to the circular path of travel. By this construction various circular 55 speeds may be obtained without the use of a governor or a centrifugal brake.

From the foregoing it is believed that the construction and operation of my fan are apparent 60 to one skilled in the art, but it is pointed out that it is merely necessary to turn on the current to start the fan in which case all other action is automatic, including proper braking of the rotational movement. Furthermore there are no fragile parts which are likely to become broken, and no exposed parts which might accumulate 65 dust and the like. The fan assembly is light, compact, and durable, and may be manufactured and sold at a reasonable figure; the exposed parts 70 may be subject to wide variation as to shape and configuration—for instance the base may be octagon shape, or oval or square; so that the design of the exposed portions of the assembly may be 75 made to conform to current artistic concepts.

Furthermore, the arrangement of the carriage and standard is such that two or more motors and fans may be used as well as one motor and fan, and the electrical contact between rings 22 and 23 with contact members 12 to insure proper flow of current under all conditions to the motor. In practice the only adjustments necessary to attain perfect operation are through the adjusting nut 36 to modify the braking action; and through wing nut 43 to alter the angular position of the fan. It is again emphasized, however, that changes in form, size position and relationship of parts are permissible provided such changes fall within the purview of the appended claims.

I claim:—

1. An electric fan comprising a stationary base portion, a fan and motor supporting portion mounted for free rotational movement on the base, said fan and motor being off-set with respect to the axis of rotation of said portion whereby to set-up a back pressure upon actuation of said fan tangential to the axis of rotation thereby to actuate the rotating portion, and a braking device operatively connected with the fan and motor assembly and functioning through centrifugal force generated by rotation of said fan and motor assembly to engage the stationary base portion with increasing pressure as the speed of rotation of the fan and motor assembly increases to form a drag, and means for regulating said pressure.

2. An electric fan comprising a stationary base portion, and a fan and motor supporting portion mounted for free rotation on the base, and a brake mechanism including a spring pressed 35 brake pin and means for regulating the effective tension of the spring associated with the fan and motor assembly and actuated by centrifugal force generated by rotation of the fan and motor assembly to control the speed of rotation of said rotating portion by engaging the stationary base part with a pressure increasing with the increase in speed of rotation of the fan and motor assembly; said pressure being exerted against the tension of the spring.

3. An electric fan comprising a stationary base portion, a fan and motor supporting portion mounted for free rotation on the base, wiping electrical contacts between the base and the rotating portions and having connections with an in-put circuit and the motor to actuate the motor during rotation of said supporting portion, a laterally extending arm, a pivoted bracket on the arm, and an adjustable mounting for the motor and fan assembly on the bracket whereby the position of the same may be changed angularly with respect to the plane of rotation, and a brake mechanism connected with the bracket and actuated by centrifugal force generated by rotation of the fan and motor assembly to control the speed of rotation of the supporting portion.

4. An electric fan comprising a stationary base portion, a fan and motor supporting portion mounted for free rotation on the base, wiping electrical contacts between the base and the rotating portions and having connections with an in-put circuit in the base, and a motor circuit in the rotating portion whereby to actuate the motor during rotation of the supporting portion, the motor and fan assembly being off-set 70 with respect to the axis of rotation of said supporting portion whereby to rotate the supporting portion through back pressure of air from the fan, and a braking mechanism operatively associated with the fan and motor assembly and 75

cooperating with a stationary element on the base for controlling the speed of rotation in proportion to centrifugal force generated by rotation of the fan and motor assembly, and said fan and motor assembly being mounted for manual adjustment to vary the angular direction of the air blast with respect to the plane of rotation thereof.

5. An electric fan comprising a stationary element and a rotating element, the fan and motor assembly carried by the rotating element in a position off-set with respect to the axis of rotation whereby to generate a back pressure upon

actuation of the fan tangential to the axis of rotation of the member; said fan and motor being mounted for slight pivotal movement in a direction at right-angles to the plane of rotation, and a braking mechanism operatively connected 5 therewith to utilize said pivotal movement to automatically control the speed of rotation of said element in proportion to the extent of centrifugal force generated, and means for manually adjusting said fan and motor assembly to direct 10 the air blast at various angles.

WILLIAM M. YOUNG.
